(57) **CLAIM**

The ornamental design for a motorcycle cover, as shown and described.

DESCRIPTION

FIG. 1 is an environmental front view of the motorcycle cover showing my new design;

FIG. 2 is a rear perspective view of the motorcycle cover;

FIG. 3 is a front perspective view of the motorcycle cover;

FIG. 4 is a front elevation view thereof;

FIG. 5 is a rear elevation view thereof;

FIG. 6 is a first end view thereof;

FIG. 7 is a second end view thereof;

FIG. 8 is a top view thereof; and,

FIG. 9 is a bottom view thereof.

The motorcycle shown in broken lines in FIG. 1 is included for the purpose of illustrating environment and forms no part of the claimed design.
